US00D717748S

(12) **United States Design Patent**
Nishimoto et al.

(10) **Patent No.:** US D717,748 S
(45) **Date of Patent:** ** Nov. 18, 2014

(54) **SET TOP BOX**

(71) Applicant: **Sumitomo Electric Networks, Inc.**,

Tokyo (JP)

(72) Inventors: **Hiroaki Nishimoto**, Tokyo (JP);
Takahiro Kusumoto, Tokyo (JP); **Kenta Tsutiya**, Tokyo (JP); **Mitsuhiro Matsuo**, Tokyo (JP); **Hiroyuki Kohama**, Tokyo (JP); **Tatsuo Yoneda**, Tokyo (JP)

(73) Assignee: **Sumitomo Electric Networks, Inc.**,
Tokyo (JP)

(**) Term: **14 Years**

(21) Appl. No.: **29/480,071**

(22) Filed: **Jan. 23, 2014**

(30) **Foreign Application Priority Data**

Jul. 25, 2013 (JP) 2013-016969

(51) **LOC (10) Cl.** **14-03**

(52) **U.S. Cl.**

USPC **D14/125**

(58) **Field of Classification Search**

USPC D14/125, 435, 356, 242, 436, 433, 474, D14/240, 496, 385, 358, 480.1-480.7; 360/97.01, 685, 686, 752, 737, 732, 360/784, 803; 439/135, 144, 139-141, 147, 439/136, 638, 518, 131; 365/51, 63, 131; 710/52, 300, 313; 711/115, 103, 154, 711/161-162; 70/58; 323/210; 713/186, 1; 382/124; 235/492; D13/147

Office Action dated Jan. 28, 2014 from corresponding Japanese design patent application No. 2013-016969 (with attached English-language translation).

Primary Examiner — Randall Gholson

(74) *Attorney, Agent, or Firm* — Drinker Biddle & Reath LLP

(57) **CLAIM**

The ornamental design for a set top box, as shown and described.

DESCRIPTION

FIG. 1 is a top perspective view of a set top box.

FIG. 2 is a front view of the set top box.

FIG. 3 is a rear view of the set top box.

FIG. 4 is a right side view of the set top box.

FIG. 5 is a left side view of the set top box.

FIG. 6 is a top view of the set top box.

FIG. 7 is a bottom view of the set top box; and,

FIG. 8 is a top perspective view of the set top box shown in an alternate configuration.

The broken lines shown in the drawings show unclaimed subject matter only and form no part of the claimed design.
